UNITED STATES PATENT OFFICE.

LEWIS R. NEISWENDER, OF PHOENIXVILLE, PENNSYLVANIA.

NIPPLE.

1,186,225.

Specification of Letters Patent.

Patented June 6, 1916.

Application filed November 12, 1912. Serial No. 730,907.

To all whom it may concern:

Be it known that I, LEWIS R. NEISWENDER, a citizen of the United States, residing at Phoenixville, in the county of Chester and 5 State of Pennsylvania, have invented new and useful Improvements in Nipples, of which the following is a specification.

My invention relates to nipples such as rubber nipples commonly used upon nursing-bottles.

One object of the invention is to provide means which may be effectively gripped by the fingers so as to enable or facilitate ready detachment of the nipple from the bottle.

Another object of the invention is to provide such means in the form of a tab or tabs which are arranged diagonally with respect to or deflected away from the bottle, to better permit the engagement of the fingers 20 therewith.

Another object of the invention is to provide an enlarged strengthening rib or flange at the junction of the tab with the body of the nipple, so that the tab or tabs will prove 25 efficient during constant use and not be likely to sever from the body.

With these and other objects in view, the invention is embodied in preferred form in the device shown in drawings accompanying 30 this application and described herein-after.

In said drawings:—Figure 1 is an elevation showing the nipple in place upon the neck of the bottle; Fig. 2 is a vertical 35 sectional view through the nipple taken at right angles to Fig. 1, and Fig. 3 is a bottom or inverted plan view of the nipple.

In the drawings like reference characters 40 designate like or corresponding parts throughout the several views.

Referring specifically to the drawings, 1 designates the body of a nipple which may be of any approved construction and is 45 preferably of the usual type made of rubber.

As usual an outlet opening such as 2 is provided. The nipple as is usual is adapted for

detachable engagement with the bottle neck, and is shown so attached to the bottle neck in Fig. 1, where the neck is designated 3.

In connection with the nipple, suitable 5 means is provided whereby the same may be gripped by the fingers on opposite sides so as to facilitate ready removal of the nipple from the bottle neck. Such means as shown, 10 consists of tabs 4 which are molded integral 5 with the body of the nipple. Such tabs it will be noted, are elongated so that a secure hold may be had thereon, and it will be further noticed that the tabs are deflected 15 outwardly from the center thereof as by 60 being inclined as shown in the drawings, and best in Fig. 2. After continued use there might be a tendency for the tabs to 65 sever or weaken at their connection with the body of the nipple, and to avoid such a 70 contingency the body of the nipple at the base or lower edge thereof, is preferably provided with an enlarged bead, rib or flange 5. It will thus be seen that the connection or junction between the body and 75 tabs is reinforced and an auxiliary finger support is provided.

In use, the deflection of the tabs 4 away from the bottle, as well as their being elongated, permits the same to be readily 75 grasped or gripped by the fingers. After thus gripping the tabs, the same are pulled upwardly so that the nipple may be removed from the bottle.

Having thus described my said invention, 80 what I claim as new and desire to secure by Letters Patent is:—

A nipple comprising a body portion having a reinforcing bead extending around its lower edge, and relatively long flexible tabs 85 extending from the bead of said body portion, said tabs being arcuate in cross section.

LEWIS R. NEISWENDER.
